UNITED STATES PATENT OFFICE.

GEORGE WACKER, OF NEW YORK, N. Y., ASSIGNOR TO HIMSELF AND JOHN J. JUNGERMANN, OF SAME PLACE.

GAS-ENGINE.

SPECIFICATION forming part of Letters Patent No. 242,401, dated May 31, 1881.

Application filed April 1, 1881. (No model.)

To all whom it may concern:

Be it known that I, GEORGE WACKER, of the city, county, and State of New York, have invented a new and Improved Gas-Engine, of which the following is a specification.

The object of my invention is to utilize the power that is obtained by the explosion of gas in a closed vessel, and to utilize the power produced by the pressure of the air on a piston at the outer end of a cylinder in which a vacuum has been formed by an explosion.

My invention consists in a gas-engine having its piston-rod pivoted to a guide-rod pivoted to the frame of the machine, to which a guide-rod one end of the connecting-rod is pivoted at or near the joint with the piston, whereas the other end is attached to the crank of the fly-wheel.

In the accompanying drawings, Figure 1 is a longitudinal sectional elevation of my improved gas-engine. Figs. 2 and 3 are diagrams of the same, showing the piston and crank in various positions.

Similar letters of reference indicate corresponding parts.

The piston-rod A is pivoted to the upper or outer surface of the piston B, contained within the water-jacketed cylinder C of a gas-engine, provided with suitable devices for admitting, mixing, and igniting the explosive gases. I will not describe these devices, as they are not the subject of my invention.

The upper end of the piston-rod A is pivoted to a guide-rod, D, which is pivoted to the frame E of the machine at F.

The connecting-rod G is attached to the crank H of the shaft J, and is pivoted to the guide-rod D at its joint with the piston-rod, as shown in Figs. 2 and 3, or between this joint and the pivot F.

A fly-wheel, K, and an eccentric wheel, L, for operating the slide M, which opens and closes the valve for admitting gas, air, &c., are mounted on the shaft J.

The operation is as follows: If the piston B is in the position shown in Figs. 1 and 2, it will be thrown upward very rapidly by the gases of the explosion. The piston will have completed

its stroke when the crank has made only about one-third of a revolution, the piston and crank connecting-rod, &c., being in the position shown in Fig. 2 when the outward stroke of the piston is completed. The crank then swings around in the direction of the arrow a', and the movement of the piston is hardly perceptible.

The gases now begin to condense and form a vacuum under the piston B, and the piston is forced downward in the cylinder C with accelerated speed by the pressure of the air.

The speed of the outward stroke is in proportion to the speed of the inward stroke as two is to one, or, that is, the piston moves twice as rapidly in the outward as in the inward stroke. But this is the result desired, for the piston must leave the cylinder very rapidly or the energy of the explosion will waste itself in vibrating and shaking the cylinder; but the piston must return slowly if the benefits of the condensation of the gases are utilized, as this condensation takes place gradually.

The cylinder may be vertical, horizontal, or inclined.

Having thus fully described my invention, I claim as new and desire to secure by Letters Patent—

1. In a gas-engine, the combination, with the frame, of a guide-rod pivoted thereto, a piston-rod pivoted to the guide-rod, a fly-wheel shaft having crank, and a connecting-rod, the latter pivoted at one end to the piston-rod and at the other to the crank of fly-wheel shaft, all constructed and arranged as and for the purpose specified.

2. In a gas-engine, the combination, with the cylinder C, of the piston B, the piston-rod A, pivoted thereto, the rod D, pivoted to the piston-rod A and to the frame E, and the connecting-rod G, pivoted to the rod D and attached to the crank H, substantially as herein shown and described, and for the purpose set forth.

GEORGE WACKER.
